UNITED STATES PATENT OFFICE.

FELIX J. RUSH, OF NEW YORK, N. Y.

CONTAINER.

Application filed November 30, 1925. Serial No. 72,116.

This invention relates to containers and has particular reference to paper or other flexible containers which are particularly adapted for holding a fluid and in such manner as to be conveniently discharged therefrom.

Among the objects of this invention is to provide a flexible or paper container having a nozzle and means within the container operative from without the container for piercing the wall thereof to form an opening through which the fluid or other material in the container may be conveniently discharged into a suitable receptacle.

Another object of this invention is to provide a container which may be formed of paper or other flexible material and is of novel shape or form so as to have its maximum cross sectional area at a point approximately intermediate of the ends thereof, said container being provided with a nozzle at the closed end, said nozzle being positioned toward a side edge of the container, and said side edges being so positioned with relation to said nozzle as to facilitate the insertion thereof into the neck or opening of a receptacle into which the material within the container is to be discharged.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a perspective view of the container with a part broken away to show the nozzle and operating mechanism used in conjunction therewith.

Fig. 2 is a fragmentary view showing the nozzle in section and with said mechanism operated to permit of a discharge of the contents of the container through the nozzle.

Fig. 3 is an enlarged sectional view on the line 3—3 of Fig. 1.

Referring now more specifically to the drawings, I show my invention as comprising a container 10 which may be formed of any suitable flexible material as, for instance, paper, said container being of relatively considerable length in proportion to

the breadth thereof and having one of its side edges 11 substantially straight throughout the length of the container, and another of its side edges 12 of angular form and with the vertex of the angle approximately intermediate the ends of the container. The result of this construction is to provide a container which has a relatively sharp slope at the edge 12 toward the edge 11 at the bottom of the container, a nozzle 13 being provided at said bottom of the container, and thus insertion of said nozzle into a neck or other opening of a receptacle into which the contents of the container are to be discharged is facilitated. The angular form of the edge 12 permits likewise of a decrease in cross sectional area of the container toward the opening 14 thereof. It will thus be seen that the maximum cross sectional area of the container is at a point approximately intermediate of the ends thereof and substantially at the vertex of the angle aforesaid. Said container is preferably formed with folds 15 and 16 at the side edges thereof which lie inwardly of the container so as to increase the compactness thereof as for purposes of packing and shipping. It will be observed that these folds decrease constantly in size toward the closed bottom of the container.

The nozzle 13 may have any suitable relation or position with reference to the main body of the container, but is preferably formed as an integral extension thereof and may be of substantially conical form as shown. While the precise method of forming or joining the walls of the container are not shown, it being understood that any convenient or practical method may be followed in this respect and that gluing or other fastening means may be resorted to, nevertheless, I show the nozzle as having seams 17 extending therearound to form a reliable junction between the sides of the nozzle and thus to effectively support such means or operating mechanism as is placed within the nozzle and is effective for rupturing the wall thereof and to permit a fluid or other material within the container to flow out of the nozzle. Said means includes a pair of levers 18 which are pivotally connected to each other as by means of a pin or eyelet 19, each of said levers having at its upper end, an arm 20, said arms being spaced from each other and being positioned adjacent to the

walls of the nozzle, the lower ends of said levers being positioned in relative proximity thereto and having suitable means or points which are effective for piercing the wall of the nozzle when the arms 20 are pressed toward each other as shown by arrows *a* directly through the walls of the nozzle by virtue of the flexibility thereof. Attachment means are provided within the container for holding the piercing means in position within the nozzle. More specifically, said attachment means take the form of a strip of paper 21 carrying a suitable tongue such as the metal member 22 which is downwardly directed to engage over the piercing means and between the arms 20 thereof. The tongue 22 is supported by said paper strip in any suitable manner as by engaging in a slit 23 thereof. Said paper strip in turn is supported by the wall of the container as by being glued thereto as shown at 24. The tongue 22 has an offset portion 25 of relatively extended size and arranged to lie against a side wall of the container beneath the paper strip 21. The levers 18 may be notched or otherwise recessed as shown at 26 so as to permit of a tilting movement of the arms 20 toward each other as stated and without in any way interfering with the precise position of the tongue 22, said notched portions being arranged for this purpose to pass beneath said tongue. The piercing means is supported in any suitable manner within the nozzle as by abutment of the arms thereof against the conical sides of the nozzle or by contact of the ends of said levers with the bottom of the spout or both. In any event, the ends of the levers 18 are preferably formed somewhat blunt and with the piercing points 27 positioned to a side. In this way should the piercing means have direct contact with the bottom of the nozzle, the same would not be pierced due to the weight of the piercing means, but the flat bottom of said levers would merely be positioned thereon so as to support the piercing means.

The operation of my invention is as follows: Should it be desired to discharge a fluid into a receptacle which may be out of the way or for one reason or another not conveniently accessible, the fluid is placed directly into the container and the neck portion 28 thereof folded about a folding line 29, said neck portion thus constituting a handle whereby the container may be conveniently carried. The nozzle 13 is then inserted into the receptacle opening such as the tube 30. Pressure is then applied at the points of the arrow *a* whereby the wall of the nozzle is pierced and the fluid flows through the opening so formed out of the container and into the receptacle.

It will be observed that my piercing means permits of proper actuation of the

same above the point where the nozzle is pierced. In this way it will be seen that there is no possibility of any of the fluid being splashed about or coming in contact with or soiling the hands of the operator. 70 Moreover, it is to be understood that the term "piercing means" is intended broadly to define any mechanism which is permanently associated with the container and is operative from without thereof for effecting 75 an opening or piercing the wall of the container. As a matter of convenience, however, my invention shows the piercing means as located within the container and operative from without as by pressure applied 80 through a flexible wall thereof.

At the mouth or opening at the top of the container, agreeable to the usual practice in the making of paper or like receptacles, the stock is folded over, making a strong reinforcement whereby when the upper end portion of the container is to be carried suspended from the hand, the person carrying it may secure a most reliable grasp upon the container and the load within it for the most 90 effective manipulation thereof. By this fact the container is not likely to become torn or ruptured due to the load, nor can the contents thereof spill or splash except as intended and otherwise herein explained. 95

I claim:

1. The herein described container comprising means within said container arranged to be actuated from without the container for piercing the wall thereof to permit the contents of the container to flow out therefrom. 100
2. The herein described container having a flexible wall comprising means within the container arranged to be actuated from without the container through said wall by flexure thereof to effect an opening in the wall of said container for permitting the contents to flow out therefrom. 105
3. The herein described container having a pierceable wall, and piercing means associated with said container and operative to pierce outward through said wall while the container is full to effect an opening in said wall of the container for permitting the contents thereof to flow out of the container. 110
4. The herein described container having a pierceable wall, and piercing means associated with said container and carried thereby permanently, said piercing means being operative to form an opening in said wall of the container for permitting the flow of the contents therefrom, said piercing means having a member whereby said piercing means can be actuated for the purpose aforesaid above the point where said opening is to be formed. 115
5. A device as set forth in claim 4 wherein said piercing means comprises a pair of levers of the first class pivotally connected 120

- to each other, said container having a flexible neck portion, said piercing means being positioned within said neck portion, whereby pressure can be exerted on said 5 piercing means through the wall of said neck to cause a relative tilting movement of said levers, the ends of said levers adjacent to the end of said neck being then effective to puncture the wall of said neck.
- 10 6. A device as set forth in claim 4 wherein said piercing means comprises a pair of pivotally connected members, said members having arms at one end of said piercing means spaced from each other, and points 15 at the other end of said piercing means, said container having a flexible neck, said piercing means being positioned within said neck and with said points adjacent to the end of the neck, whereby pressure can be exerted 20 on said arms through the walls of said neck to cause said points to pierce the wall of the neck, and means normally holding said piercing means against accidental removal from the neck.
- 25 7. A device as set forth in claim 4 wherein said container is provided with a neck, and said piercing means is positioned within said neck, said neck being flexible to permit said piercing means to be actuated 30 through the wall of said neck, said piercing means having abutment relation with the wall of said neck whereby the same is re-

tained in said neck after an opening has been formed therein as aforesaid.

8. A paper container having a body of 35 relatively considerable length in proportion to the breadth thereof, said body being of a maximum breadth intermediate of its ends, and decreasing in width toward the open end of the container and rather sharply toward 40 the closed end thereof, said container having a nozzle at the closed end thereof to facilitate the discharge of a fluid therefrom.

9. A paper container as set forth in claim 8 wherein said nozzle is positioned in spaced 45 relation to the axis of the container and nearer to one edge thereof than to another.

10. A container of relatively considerable length in proportion to breadth, said container being of relatively flat form and having one edge thereof of substantially angular form and with the vertex of the angle approximately intermediate the ends of the container to form a container having the maximum width at said vertex, the 55 other edge of said container being substantially straight, said container having a nozzle at the closed end thereof adjacent to the straight edge of the container, said angular edge making a relatively 60 sharp angle to the nozzle.

In testimony whereof I affix my signature.

FELIX J. RUSH.
